UNITED STATES PATENT OFFICE.

MAHLON E. LAYNE AND SAMUEL N. HALL, OF LOS ANGELES, CALIFORNIA; SAID HALL
ASSIGNOR TO SAID LAYNE.

WELL MECHANISM.

Application filed September 8, 1920. Serial No. 408,944.

To all whom it may concern:

Be it known that we, MAHLON E. LAYNE and SAMUEL N. HALL, both citizens of the United States, residing at Los Angeles, in 5 the county of Los Angeles and State of California, have invented certain new and useful Improvements in Well Mechanism, of which the following is a specification.

The invention relates to well mechanism 10 and particularly to means whereby the sections of the discharge casing and the enclosed oil casing and shafting may be conveniently shipped and installed and whereby all the working parts are protected against 15 rust and dirt and against distortion of the shaft and its oil casing in shipping and handling. The ordinary centrifugal pump mechanism comprises the pump which is usually submerged in the water, a well casing 20 lining the bore of the well and power transmission and discharge apparatus extending to the surface of the ground. This apparatus comprises a discharge casing concentrically arranged with respect to the well 25 casing, a shaft or oil casing inside the discharge casing, and a drive shaft inside the shaft or oil casing and extending from the pump runners to the surface of the ground where it is connected with suitable driving 30 mechanism. As the pump may be located at a distance of from 50 feet to several hundred feet below the surface of the ground, the various casings and the shafting are made in relatively short sections for convenience in handling and shipping and these 35 sections are assembled in the field, section after section being added as the pump is lowered from the surface of the ground. Heretofore it has been the practice to ship 40 the sections of casing and shafting in long boxes the lengths being greased to protect them during transit and before installation. This method of procedure is objectionable for several reasons. The boxes containing 45 the apparatus are often exposed to the weather and the contents becomes wet and rusty before it is installed. The parts are ordinarily greased in order to protect them and when these parts are installed they are 50 apt to become covered with sand or dirt due to the installation in the field, which sand or dirt gets into the bearings to a greater or less extent and causes rapid wearing. Fur-

thermore, the shock or vibration incident to transporting the shafting in boxes is apt to 55 cause springing or distortion and such distortion even tho' relatively slight causes binding between the shaft and its bearings increasing the wear and power consumption.

Our invention is designed to provide a 60 method of storage transportation and handling which will avoid the foregoing objections, and, briefly stated, consists in utilizing each discharge casing section as a storage or shipping container for the corresponding section of shafting and shaft casing. This is accomplished by providing caps for the discharge casing sections which not only form closures protecting the contents of the casing but also assist in holding 65 the shaft and shaft casing section securely in position inside the discharge casing. In its preferred form at least one of the caps provide with screw engaging means for the shaft and shaft casing sections so that tension can be applied to such parts thus serving to hold these parts perfectly straight, 70 so that there is no distortion during transportation or handling. The caps employed may be either screw threaded to the couplings at the end of the discharge casing or may be clamped tightly in position by other means so that even under the most unfavorable conditions as to exposure and moisture 75 the contents of the container are kept perfectly clean and dry. When the apparatus is installed, it can be elevated to a vertical position before taking off the caps and can then be assembled from this position so that 80 neither the shaft section nor the shaft casing section comes in contact with the ground and as a result these parts are not exposed to the dirt or sand at the time of 85 installation. Certain embodiments of the invention are illustrated in the accompanying 90 drawings, wherein—

Figure 1 is a longitudinal section through one form of the container with the parts in position therein. Fig. 2 is a section showing the apparatus of Fig. 1 suspended for 100 installation and partially disassembled. Fig. 3 is a section similar to that of Fig. 2 but with the parts still further disassembled. Fig. 4 is a vertical section through a portion of the apparatus after it is assembled 105 and inserted in the well bore. Fig. 5 is a

section through a modified construction, and Fig. 6 is a partial section still with still another modification.

Referring first to the construction as actually installed in the well, this is shown in Fig. 4 wherein 1 1 1 are the discharge casing sections provided at their ends with the couplings 2 and 3; 4 4 4 are the shaft casing sections which serve to protect the shaft and carry the bearings for supporting the shaft; 5 5 5 are shaft sections secured together by the coupling 6 6; and 7 7 are bearings for the shaft. The bearings are supported by means of the spiders 8 8 integral with the couplings 2 and 3 and carrying the sleeves 9 9 which are integral with the spider. In order to prevent the bearings turning with respect to the sleeves 9 9 the split tapering bushings 10 10 may be employed which are forced down into position and held by means and of the opposing ends of the shaft casing sections just above.

The means whereby the discharge casing 1 is utilized as a container for the shaft casing and shaft will now be clear on reference to Fig. 1, which shows these parts in condition for shipment. A pair of closure caps 11 and 12 are employed, such caps being preferably made of rounded shape and being provided with shoulders 13 for abutting suitable shoulders on the coupling members 2 and 3. If desired gaskets or other suitable means may be employed to make the closure tighter; this being unnecessary, however, if the contacting surfaces between the caps and couplings are machined. In this type of construction the caps are perforated and one end of the shaft section 5 extends through the cap 2 and carries the nut 14. The bearing 7 at this end of the casing is supported by the spider 8 and the shaft casing section is held in position by means of the nut 15 which bears against the split bushing 10. At the other end of the casing a shaft extension 16 is employed, such shaft extension extending through the cap 12 and being provided with the nut 17. The inner end of the shaft extension is threaded to the interior of the shaft casing 4 at 18 and to the shaft coupling 6 at 19 so that on tightening the nut 17 the shaft and shaft casing sections 5 and 4 are placed under tension thus insuring that these parts will not be distorted or injured in any way during transportation.

Fig. 2 illustrates the method of handling the casings at the point of installation. The nut 14 is removed after which the cap 11 is withdrawn and the nut 15 unscrewed. The members 21 and 22 respectively are then screwed to the shaft section and shaft casing section as illustrated and the parts lifted to the position indicated by means of the split collar 20 supported from above by suit-

able lifting device (not shown). This permits the parts at the lower end of the case to drop down to the position indicated after which the nut 17 and cap 12 are removed and the extension shaft 16 unscrewed.

The removal of the extension shaft 16 permits the shaft section 5 to move down to the position illustrated in Fig. 3. The parts are now in a convenient position for coupling to the corresponding sections which have already been placed in the well, the shaft and shaft casing being coupled to corresponding sections beneath and the coupling 3 being coupled to the coupling on the discharge case section lying below.

In this way the various casings and shaft sections may be transported to the point of use and kept perfectly dry and clean during transportation and maintained against injury under the roughest treatment. Furthermore, the arrangement permits of a very rapid and easy installation without exposing any of the parts to contact with the ground, so that the shafting and bearings are assembled in a clean condition and without the sand and grit which is ordinarily picked up during the installation operation.

The type of coupling 2 not only co-operates most advantageously with the closure caps to make a satisfactory container but also has other advantages as a part of a pump discharge casing. These couplings are secured to the pipe 1 by means of the usual tapered screw connection 23 (Fig. 4) after which they are held against unscrewing by means of the rivets 24 or other suitable means. The other end of the coupling is machined straight, (not tapered) and screw threaded as indicated clear to the machined shoulders. In this way the length B (Fig. 4) of the discharge casing section is made exact and definite so that when assembled the discharge casing may be made to correspond to the length of the shaft casing and shaft, thus eliminating the necessity of cutting any of the sections to fit in the field such as has heretofore been necessary where ordinary threaded pipe couplings have been used for securing together the sections of the discharge casing. Such couplings always screw together a more or less indefinite amount when brought together to a tight position so that the over-all length of the casing can never be definitely determined until the parts are assembled. The construction is also advantageous as compared with flanged couplings since flanged couplings occupy more space laterally thus requiring a larger well casing altho such construction may be made definite as to over-all length. It will be seen that the present coupling construction occupies no more space laterally than the ordinary screw coupling sleeve and at the same time provides for giving a fixed

and definite length to the casing when assembled in the field.

Fig. 5 illustrates a modified form of cap construction, such modified form being primarily due to screw threading the caps 27 and 28 in place instead of having such caps merely fit over the couplings 2 and 3 as in the construction of Fig. 1. The upper cap 27 is provided with an extension 29 which is threaded at 30 to the shaft casing 31 and at 32 to the sleeve 33. At the other end of the casing 1 the cap is merely screw threaded to the coupling 3, the shaft casing being held by the spider 34 which engages the bearing 35 and the shaft, being held by the nut 36. This type of construction is somewhat more expensive than that of Fig. 1 but has the advantage of giving a tight connection between the caps and the couplings 2 and 3 without the necessity of using gaskets, and the heads not being perforated, are less accessible to moisture and give a smoother outer surface so that the casing may be more readily moved around upon their ends without catching than the construction of Fig. 1 wherein the nuts are employed for placing the parts under tension.

Fig. 6 illustrates a modification which may be employed at the lower end of the construction of Fig. 5 in those cases in which the spiders 34 of Fig. 5 are not used. When these spiders are not used it is necessary to provide other means for supporting the end of the shaft casing and this is accomplished by the use of the sleeve 37 which is screw threaded to the bearing 35, the cap 38 being perforated to provide for the passage of the sleeve. A second sleeve 39 with a closed end 40 fits into sleeve 37 and screws over the end 41 of the shaft section 41. Other modifications of the broad idea will be readily apparent to those skilled in the art.

What we claim is:

1. In combination in well mechanism, a discharge casing section, a shaft casing section in the discharge casing section, a shaft section in the shaft casing section, and closure caps for the discharge casing section, one of said caps being arranged to support the ends of shaft section and shaft casing section adjacent thereto.

2. In combination in well mechanism, a discharge casing section, a shaft casing section in the discharge casing section, a shaft section in the shaft casing section, and closure caps for the discharge casing section, one of said caps being arranged to support the ends of shaft section and shaft casing section adjacent thereto, and to apply tension thereto.

3. In combination in well mechanism, a discharge casing section, a shaft casing sec-

tion in the discharge casing section, a shaft section in the shaft casing section, and rounded closure caps secured to the ends 65 of the discharge casing section arranged to maintain the shaft casing and shaft sections in concentric relation.

4. In combination in well mechanism, a discharge casing section, a shaft casing section in the discharge casing section, a shaft section in the shaft casing section, closure caps for the discharge casing section and connections between such closure caps and the shaft casing and shaft sections for maintaining such sections in concentric relation. 75

5. In combination in well mechanism, a discharge casing section, a shaft casing section in the discharge casing section, a shaft section in the shaft casing section, closure 80 caps for the discharge casing section, and screw connections between one of said caps and the shaft casing and shaft sections for holding such sections.

6. In combination in well mechanism, a discharge casing section having at its ends unions provided with closure caps fitting over the ends of said section, a shaft casing section in the discharge casing section, a shaft section in the shaft section casing, and 90 connections between one of said caps and the shaft casing and shaft sections.

7. In combination in well mechanism, a discharge casing section having at its ends unions provided with closure caps fitting 95 over the ends of said section, a shaft casing section in the discharge casing section, a shaft section in the shaft section casing and screw connections between said caps and the adjacent ends of the shaft casing and 100 shaft sections for applying tension to said sections.

8. In combination in well mechanism, a discharge casing section, a shaft casing section in the discharge casing section, a shaft 105 section in the shaft casing section, closure caps for the discharge casing section one of which is perforated and connections extending through such perforated cap and forming a closure therefor and connected to the 110 shaft casing and shaft sections.

9. In combination in well mechanism, a discharge casing section, a shaft casing section in the discharge casing section, a shaft section in the shaft casing section, closure 115 caps for the discharge casing section one of which is perforated and connections extending through such perforated cap and having screw connections with the shaft casing and shaft sections for holding such sections and 120 applying tension thereto.
